PIPE WRENCH

Delbert Cole, Hollydale, Calif.

Application January 22, 1949, Serial No. 72,203

3 Claims. (Cl. 81—66)

1

This invention relates to a pipe wrench, generally, and more particularly, deals with a wrench or tongs adapted to handle drill pipe, well casing in the well-drilling field.

In well-drilling, drill and casing pipe varies in outside diameter between a present minimum of 2 $\frac{1}{2}$ inches and a maximum of 8 $\frac{1}{2}$ inches. In my two earlier patents, Nos. 2,224,142 and 2,243,272, I provided a pipe wrench or pipe tongs that would handle pipes varying considerably in size but which, however, could not have universal use because the limit of variation was in the nature of some three inches. Consequently, the range of pipes in the smaller sizes were handled by one wrench and those in the larger sizes by another.

An object of the present invention is to provide a pipe wrench of novel form that is adapted to handle all sizes of pipes conventionally used in well-drilling and in the maintenance of flowing wells.

Another object of the invention is to provide a pipe wrench structure that embodies two selective pipe-gripping positions, the smaller thereof being adapted to handle a range of small pipes and the larger thereof a range of larger pipes.

A further object of the invention is to provide a pipe wrench, as indicated, in which the larger station is additionally adjustable for greater flexibility in use.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a face view of a wrench according to the present invention, with the handle thereof broken away, and showing the same applied to a pipe in the smaller range of pipe sizes.

Fig. 2 is a side elevational view thereof.

Fig. 3 is a longitudinal sectional view taken through the elements of the wrench and showing the same applied to a pipe in the larger range of pipe sizes.

2

The pipe wrench that is illustrated comprises, generally, a handle 5, a jaw link 6 pivotally connected to the handle and associated with a wedge cam 7 formed on said handle, a latch link 8 pivotally connected to the free end of the jaw link 6, a keeper link 9 having adjustable engagement with the latch link 8, a link 10 pivotally connecting the handle 5 and the keeper link 9, and resilient means 11 for urging the latter link into operative latched position. The handle and links above provided, in all operative positions of the wrench, comprise an articulate pipe-encircling structure that, with easy facility, can be applied to handle pipes varying up to three and one-half to four times the size of a minimum pipe size.

The handle 5, at the end where it carries links 6 and 10 and on the side toward which link 6 is directed, is provided with the wedge cam 7. The latter comprises a convex edge on the handle that is provided with teeth or like pipe-gripping means to obviate slippage.

The pivots for links 6 and 10, designated 12 and 13, respectively, are arranged longitudinally of the handle with the latter at the inner end of the handle and the former immediately adjacent thereto.

The jaw link 6 is formed with a recess 14 for receiving a pipe in the smaller range of sizes, said recess being defined by a toothed gripping face 15 and a relatively angularly related face 16 which, if desired, may be similarly roughened. The pipe *P* is adapted to reside in said recess against faces 15 and 16 and to be wedged therein by wedge cam 7 upon rotation, in a clockwise direction, of the handle about pivot 12.

The jaw link 6, at its free end, carries a pivot 17 that connects it with link 8 and, between said pivot and wall 15, there is provided a convexly curved toothed wall 18 which forms one of the jaws for engaging a pipe *P* in the larger range of sizes.

The latch link 8, at its outer free end, is provided with three abutment steps 19, 20 and 21, that are successively nearer to pivot 17. Two or more than three such steps may be provided, as desired. Said steps have selective engagement with keeper link 9 and each is provided with a shoulder 22 that limits the position of the latter link when engaged with each respective step.

The step 19 defines one edge of a curved projection 23 that forms the outermost end of link 8, said projection, in a direction toward the pivot 17, having a concavely curved face at 24, said face being approximately transversely across from step 21 on the opposite side of said link. Be-

tween pivot 17 and curved face 24, said link is provided with obtusely angularly related toothed gripping walls 25 that cooperate with wall 18 of link 6 to grip a pipe P.

The keeper link 9 is connected to link 10 by a pivot 26. Said keeper link, at its free end, is provided with an elongated outwardly curved handle part 27 and between said part and the pivot, with a longitudinal slot 28, said slot, between link 10 and a shoulder 29 defining the handle part, being of such extent that the same is receptive of link 8 when face 24 is engaged with link 8 and step 21 is engaged with said shoulder 29. When so engaged (Fig. 1), projection 23 protrudes through slot 28 and any force seeking to withdraw link 8 from the slot is counteracted by the convexly curved edge 30 of said projection. In other words, link 8 cannot be withdrawn from engagement with link 9 by a pull in the direction of pivot 17, but the keeper link 9 can be rotated on its pivot 26 to effect separation from the latch link.

The keeper link, on the inner side thereof, is provided with a pair of stop lugs 31 adjacent pivot 26 and with an abutment 32 opposite to said stop lugs.

The link 10, on its inner side, is provided with obtusely angularly related gripping faces 33 that complete the encirclement of a pipe P and cooperate with faces 18 and 25. On the opposite side, said link is formed with a seat 34 for a compression spring 35 that is confined by abutment 32 of link 9. Said spring exerts its force in a direction to rotate link 9 inward about its pivot 26. To limit such rotation, link 10 is provided with abutment shoulders 36 that engage stop lugs 31. It can be seen therefore, that the means 11 which comprises spring 35 and related elements, acts at all times to urge link 9 into engaged cooperation with latch link 8.

When being applied to pipes in the small range of sizes, links 8 and 9 are disengaged and link 6 swung out on its pivot 12 to admit the pipe between wedge cam 1 and the inner end of face 8 into recess 14. Links 8 and 9 are then re-engaged as in Fig. 1. Movement of handle 5 in a clockwise direction will cause relative movement of pivots 12 and 13, resulting in link 6 exerting a pull on link 8, and link 10 exerting a pull on link 9. Links 8 and 9 are, therefore, held interlocked as the wedge cam and wall 15 grip pipe P. Continued clockwise movement of handle 5 will rotate said pipe in a clockwise direction. A top-for-bottom reversal of the wrench will rotate said pipe in the opposite direction.

For pipes which will not comfortably enter recess 14, the arrangement of Fig. 3 is used. For the largest of the larger pipes P, step 19 is engaged with shoulder 29. Now, as the pivots 12 and 13 are moved relatively by clockwise movement of handle 5, the same opposed pulls on links 8 and 9 hold them engaged so that the gripping

faces 18, 25 and 33 can effect rotation of the pipe. A slight counter-clockwise movement of the handle 5 will permit separation of links 8 and 9.

For sizes of pipes between pipes p and P, step 20 or 21 may be engaged with shoulder 29 with like results.

While the invention that has been illustrated and described is now regarded as the preferred embodiment, the construction is, of course, subject to modifications without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. In a pipe wrench, a series of four pivotally connected links arranged to encircle a pipe, a handle pivotally connecting two of the links and movable to articulate said circle of links, three of said links having pipe-gripping walls directed toward each other, means separably and adjustably connecting the two links that are not connected to the handle, and wedge cam and jaw means on said handle and one of the links connected therewith for gripping a pipe of a size smaller than can be gripped by the mentioned three links.

2. In a pipe wrench, a series of pivotally connected links arranged to encircle a pipe, a handle pivotally connecting two of said links and movable to articulate said circle of links to grip a pipe encircled thereby, and wedge cam and jaw means on said handle and one of the links connected therewith for gripping a pipe of a size smaller than can be gripped by the mentioned circle of links.

3. In a pipe wrench having a handle and a series of pivotally connected links pivotally carried by an end of said handle, said links being arranged to encircle a pipe and the handle being movable to articulate said links to grip a pipe encircled thereby, the improvement that comprises a wedge cam and jaw means on said end of the handle and one of said links for gripping a pipe of smaller size than can be gripped by the mentioned circle of links.

DELBERT COLE.
